UNITED STATES PATENT OFFICE.

NEKOLAI DAHL, OF TRONDHJEM, NORWAY.

BOX-FASTENER.

No. 909,161.

Specification of Letters Patent.

Patented Jan. 12, 1909.

Application filed August 25, 1908. Serial No. 450,189.

To all whom it may concern:

Be it known that I, NEKOLAI DAHL, merchant, a citizen of the Kingdom of Norway, residing at Fjordgaden 82, city of Trondhjem, Norway, have invented a new and useful Improvement in Box-Fasteners; and I do hereby declare the following to be a full, clear, and exact description of the same.

In my United States Patent No. 900084, I have described a box-fastener adapted especially for closing boxes serving for shipment of herrings and other fish. The said box-fastener comprises two elastic levers turnably arranged on opposite sides of the case or box, each lever provided, at its upper part, with an angle piece the upper hook-like portion of which projects over and against the top surface of the cover or over and against the surface of a recess in the cover. The said portion is brought against the cover to press it fast in closing position, by turning the lever obliquely to one side. When using the described fastening-device, it is necessary (in order to bring the same securely in closing position) to strike the angle piece, which, however, often results in the latter taking a wrong position, or the rivet connecting it with the lever being torn off.

My present invention has for its object to provide a box-fastener which does not have the drawback above mentioned, so that the device, especially in point of security, is superior to that formerly known.

The invention is illustrated in the accompanying drawing, in which:

Figure 1 is an elevation of a box or case provided with my improved fastener; Fig. 2 is an enlarged front view of the fastener; Fig. 3 is a sectional view, on the line I—I of Fig. 2, showing also a portion of the box and cover against which the hooked end of the fastening is gripped; and Fig. 4 is a sectional view on the line II—II of Fig. 2.

3 is the rivet joining the turnable lever to an angular piece, 4, 5, as described in my prior patent. The cover of the box may be made up of the central removable part, 6, and of the fixed side parts or boards, 8. 7 represents an edge recess in said removable part, while 19 represents an edge recess in the left hand fixed part 8. Into the latter recess or into both of these recesses, according to the position of the fastening device, the overhanging hooked portion, 5, of the fastening device projects and presses against the

top surface of the same, when the lever is turned obliquely to one side.

The removable part, 6, of the cover has one or more strips, 11, secured thereto, which are formed so as to extend (as shown in Fig. 1) underneath a board of the fixed part, 8, of the cover. Now, in order to prevent the necessity of hammering or bending the angle piece, 4, 5, during the fastening or releasing of the device, the lever of my former patent is, according to the present invention, replaced by a plate, 12, which, at an end, 16, projecting therefrom, is provided with a raised portion 13, having enlargements or edges, 14, which may be struck, or hammered, when the lever or plate is to be turned to either open or to close the device.

The plate is preferably made nearly circular, and has an upper portion, 15, carrying the rivet, 3, diametrically opposite the extension, 16. Partly in order to strengthen the plate laterally, and partly in order to increase its frictional resistance against turning, the plate where it rests against the box wall, is provided with a curved rib, 17 (see Fig. 4), and the somewhat raised central part of the plate is quite tightly held by pivot 18, and the rib, 17, is constantly and elastically pressed against the box side, as indicated in Fig. 3, thus providing a safe frictional effect, which assists in holding the parts in the position given, and which has proved to be quite sufficient for preventing any unintended opening of the box.

Figs. 1 and 3 show the device in position and holding the removable cover part tightly to the box. The swinging of the projection, 16, to the left has caused the hook (4, 5) to be drawn down, as far as possible, into the groove 7, and to press upon the removable cover-part, 6. To release the cover, it is necessary only to turn the device to the position shown in Fig. 2, whereupon the hook (4, 5) will be lifted upwardly, out of the groove, 7, and out of the path of the removable cover-part, 6.

Having now described my invention, what I claim as new and desire to secure by Letters Patent is:—

1. A packing case, or the like, having a removable cover, in combination with a device for holding the cover in place and for permitting removal of the same, said device consisting of a metal plate pivotally secured on one side of the case and provided

with raised side portions for facilitating the turning of the plate, and of a hook pivotally carried by the free upper end of said plate and having the hook end thereof projecting inwardly for engaging the top of the cover.

2. A packing case, or the like, having a removable cover, in combination with a device for holding the cover in place and for permitting removal of the same, and consisting of a plate pivotally connected with the side of the box having a curved rib exerting an elastical engagement with said

side, and of a hook pivotally carried by the free upper end of said plate and having the hook end thereof projecting inwardly for 15 engaging the top of the cover.

In testimony whereof, I have signed my name to this specification in the presence of two subscribing witnesses.

NEKOLAI DAHL.
